UNITED STATES PATENT OFFICE.

WILLIAM PARKIN, OF TAUNTON, MASSACHUSETTS, ASSIGNOR TO REED & BARTON, OF SAME PLACE.

DESIGN FOR COFFIN-PLATES.

Specification forming part of Design No. 7,398, dated April 28, 1874; application filed March 31, 1874.
[Term of Patent 7 years.]

CASE C.

To all whom it may concern:

Be it known that I, WILLIAM PARKIN, of Taunton, in the county of Bristol and State of Massachusetts, have invented a Design for Coffin-Plates, of which the following is a specification:

The invention relates to a peculiar configuration of coffin-plates, whereby a novel design may be formed and a pleasing effect produced upon the beholder.

The invention will first be fully described, in connection with all that is necessary to a full understanding thereof, and then pointed out in the claim.

The figure represents a plan view of my invention.

A is the main raised face of the coffin-plate, curved on the top and bottom lines $a a'$ and flanked on each side by a hollow ornamental

post, B. In the upper concavity of the face A is placed the bouquet-holder C, rising to about the same altitude as the posts B. From the lower convexity of face A depends the bordering D, composed of end-rounded and florally-decorated parts d, increasing in their downward projection from each end toward the middle.

What I claim as my invention is—

A design in coffin-plates, consisting of the raised faces A, curved on the lines $a a'$, the side posts B B, and the lower border D, the latter composed of parts d, increasing in their downward projection from each end to the middle, all as shown and described.

WILLIAM PARKIN.
